UNITED STATES PATENT OFFICE.

ROBERT G. C. BOA, OF NEW YORK, N. Y., ASSIGNEE TO REMINGTON ACCOUNTING MACHINE CORPORATION, OF NEW YORK, N. Y., A CORPORATION OF NEW YORK.

CALCULATING MACHINE.

Application filed June 22, 1921. Serial No. 479,580.

To all whom it may concern:

Be it known that I, ROBERT G. C. BOA, citizen of the United States, and resident of the borough of Manhattan, city of New York, in the county of New York and State of New York, have invented certain new and useful Improvements in Calculating Machines, of which the following is a specification.

10 My invention relates to calculating machines and especially to combined typewriting and calculating machines.

15 My invention has for its principal object to provide improved means for securing in adjusted position a part of a calculating machine and more specifically to provide improved means for securing to its truck the adjustable totalizer of a combined typewriting and adding machine.

20 To the above and other ends my invention consists in certain features of construction and combinations and arrangements of parts, all of which will be fully set forth herein and particularly pointed out in the claims.

25 In the present instance I have shown my invention applied to a Remington-Wahl combined typewriting and calculating machine.

30 In the drawings,

Figure 1 is a front elevation with parts broken away of the main truck with a totalizer shown in section on a line just in front of said truck.

35 Figure 2 is a fragmentary side elevation with the truck shown in section about on the line 2-2 of Fig. 1 and looking toward the left.

40 Figures 3 and 4 are fragmentary plan views in section on the line 3-4 of Fig. 2, the parts being shown in locking position in Fig. 3 and in releasing position in Fig. 4.

45 Figure 5 is a front view of the lower right-hand part of the truck, partly in section on the line 5-5 of Fig. 6.

50 Figure 6 is a fragmentary right-hand end elevation of the bottom part of the truck and a corner of the totalizer with a part shown in section.

55 Figure 7 is a similar left-hand end view of the truck.

Figure 8 is a plan view of a certain shifting bar.

55 Figure 9 is a similar view of a certain locking bar.

Figure 10 is a fragmentary rear view of said locking bar, partly in section on the line 10-10 of Fig. 9.

Figures 11 and 12 are plan views of the shifting bar with a certain lug shown in section, the parts being in locking position in Fig. 11 and in releasing position in Fig. 12.

In the drawings Figs. 5, 6, 7, 10, 11 and 12 are on a much larger scale than Figs. 1, 2 and 4, and Figs. 8 and 9 are on a smaller scale.

In the drawings I have shown only so much of the machine as is necessary to illustrate the application of my improvements thereto. The balance of the machine 70 may be identical with that shown and described in the patent to Wahl No. 1,270,471, dated June 25, 1918. Said patent shows a Remington typewriter with a calculating machine attached thereto and comprising a 75 truck which, except as hereinafter pointed out, is like the one shown at 11 in my present drawings. Said truck is adapted to travel across a stationary calculator framework, being propelled and controlled by the 80 typewriter carriage to which it is connected by means including certain brackets 12 (Fig. 1) secured to the truck 11 by screws 13, there being one bracket at each end of the truck. Said truck may carry any desired number of totalizers 14 which by the 85 travel of the truck are caused one at a time to move across the main master wheel which is operated by the numeral keys of the typewriter and which operates the mechanism 90 of the totalizer. The machine also comprises a cross footing totalizer which is mounted on an independent truck and said independent truck may be connected up to any totalizer 14 by means of certain coupling devices including a hook 15 and an arm 16 the former of which draws the cross footer truck along and the latter of which prevents said cross footer truck from moving further to the left than the main or 95 vertical totalizer to which it is connected. At the end of a computing zone, these coupling devices are cammed loose from the totalizer 14, to be picked up again by the same or another totalizer, all as explained 100 in said patent to Wahl.

The truck 11 has two dove-tail flanges 17 and 18 and the casing plates of the totalizers are shaped to fit these flanges so that the totalizer has a dove-tail mounting on the 110

truck. A bar 20 secured by screws to the front face of the truck, has teeth 21 on its upper edge. In each totalizer there is a rock shaft 22 having rigid thereon two arms 23 and 24 which are pulled down by a spring 25 and this rocking frame can be operated against the tension of said spring by a handle, not here shown. The rear ends of the arms 23 and 24 hook down over the upper dove-tail flange 17, the tension of the spring 25 holding the totalizer snug against the truck. The right-hand arm 23 is shaped into a tooth 29 that enters between two of the teeth 21 and locks the totalizer in place. By operating the above mentioned handle the arms 23 and 24 can be raised and the totalizer can be slid to any desired letter space position longitudinally of the truck and locked there by said tooth 29. The coupling device 15, 16 takes hold of a lug 26 which projects downward from the rear corner of the right-hand frame plate. The corresponding lug 27 (Fig. 7) of the left-hand frame plate does not extend downward far enough to be engaged by this device.

The spring 25 holds the totalizer snugly in place but the locking tooth 29 is at the upper part of the totalizer and the lug 26 of the totalizer is at the lower part thereof. Under these conditions it is deemed preferable to lock the totalizer positively to the truck at a point closer to the point of engagement of the hook 15 than has heretofore been done. This is found especially desirable where the machine is operated vigorously and especially in that form of the machine shown in the patent to Wahl No. 1,349,024, dated August 10, 1920 and in which the cross footing truck is made longer so as to accommodate two totalizers instead of one. In this machine the weight that is controlled by the couplers 15, 16 is considerable, and better results are obtained if the vertical totalizer is positively locked to the truck at or near the lug 26; and this is accomplished by my present invention.

The lower part of the truck 11 is made of a cross section somewhat different from that shown in the Wahl patents above referred to, and a forwardly facing groove 30 (Fig. 2) is cut in said truck and in said groove there are movably mounted a locking bar 31 and a shifting bar 32, the former overlying the latter. The locking bar 31 has a series of teeth 33 projecting from its forward edge, said teeth being preferably more or less beveled as shown, and the notches between them being of a width to take hold of the lug 26 of the totalizer. This bar 31 is capable of sliding forward to the position shown in Fig. 3 where its teeth are in locking engagement with said lug 26 and rearward to the position shown in Fig. 4 where said teeth are free of said lug and the totalizer can,

therefore, be adjusted to the right or left along the truck. At intervals in its length the bar 31 has small round lugs or pins 34 projecting downward therefrom into cam slots 35 in the shifting bar 32. The number of these pins would depend on the length of the bars which depend on the length of the truck, which in turn corresponds to the length or width of the typewriter carriage. These parts are manufactured of various lengths according to the width of the paper that it is desired to use in the typewriter. The pins or lugs 34 can be made in any suitable way, as for example, by riveting them in the bars. In the present instance they are made by punching a depression 36 (Fig. 10) in the bar 31, this being done by means of a die or punch when said bar 31 is lying on another die having a round hole directly under said punch. Said punch is forced partway through the bar, thus forcing part of the metal down into said round hole and thus producing a lug or pin. This however is merely a shop expedient and as far as my invention is concerned the lug 34 can be made in any suitable way.

Each of the slots 35 has its ends lying parallel with the length of the shifting bar 32 and its middle part inclined so that when said shifting bar is pushed toward the left as shown in Fig. 3 the pin 34 is forced toward the front of the machine and when said shifting bar is pushed toward the right as shown in Fig. 4 said pin is cammed to the rear; and in each position the pin 34 lies in a parallel or dwell portion of the slot 35, so that bar 31 is positively held in its locking or in its releasing position.

The Wahl machine as heretofore constructed comprises a rack bar 37, the teeth of which are engaged by a certain dog shown in the Wahl patents above referred to, to lock the truck against longitudinal motion during the operation of the totalizer, this rack being secured to the front face of the truck by means of screws 38 (Fig. 1). I utilize said rack bar 37 to close the lower part of the groove 30 in front of the shifting bar 32 which shifting bar is made of a width equal to the depth of said groove so that whereas this bar can slide lengthwise right and left, it cannot move front and back, being restrained between the rack bar 37 and the bottom of the groove. On the other hand, the locking bar 31 is made of a length substantially equal to that of the truck and the ends of the groove in the truck are closed by plates 40 (Figs. 5, 6 and 7) held in place by screws 41 and dowel pins 42. These plates 40 prevent longitudinal motion of the locking bar 31 but allow it to move front and back. This it does equally at all parts of its length on account of the pins 34 and slots 35 being distributed along the bars.

The shifting bar 32 has at least one of its ends and preferably at both a projecting part 43 narrower than the balance of the bar and forming a shoulder 44. Preferably the end of this part where it projects beyond the end of the truck is bent downward to form a handle or finger piece 45. Each of the plates 40 has a slot 46 cut therein so as to accommodate the part 43 but terminating at the rear just back of said part 43 so that the shoulder 44 cannot pass beyond the end of the truck. The parts are so constructed and proportioned as to allow the bar 32 to be pushed or pulled to the right or left a distance approximating the length of the slot 35 but no farther. When said bar is in its extreme right-hand position as shown in Figs. 4 and 12 the locking bar 31 is pulled to unlocking position and when said shifting bar is moved in its extreme left-hand position as shown in Figs. 1, 3 and 11 then the locking bar 31 is in locking position.

In order to retain the shifting bar 32 in its adjusted positions any suitable detent can be employed. As here shown said bar has near its right-hand end two depressions 47 into which a ball 48 is adapted to be pressed by a compression spring 50. Said ball occupies a suitable hole drilled upward from the lower edge of the truck 11 and the spring 50 is seated in an annular depression in a bracket 51 which is secured by a screw 52 to the under side of the truck 11. The construction is such that the bar 32 can be moved from one of its positions to the other by the exertion of a little force, but the ball 48 will prevent it from accidentally jarring out of place. Since the ends of the slots 35 are parallel to the length of the truck the pins 34 are positively held in their forward or back positions.

It will be seen that any desired number of vertical totalizers can be mounted on the truck and adjusted to their respective positions in the same manner as heretofore and that then the bar 32 can be shifted to its left-hand position causing the locking bar to be projected forward and to take a positive locking hold on the lugs 26 of all of said totalizers, thus positively locking them against right or left-hand displacement at a point quite close to that at which the coupling device 15, 16 exerts a right or left-hand force on said totalizers.

In the Wahl machine, the vertical totalizers 14 are sometimes replaced by so called "dummies," these being frameworks similar to the frame of a totalizer but containing no computing mechanism. For the purposes of my invention, I consider these "dummies" to be the same as totalizers.

The locking bar 31 and its adjuncts can be used alone and the upper rack 20 can be omitted, if desired. Where several totaliz-

ers are employed, however, it is preferable to retain the upper rack, so that the various totalizers can be adjusted to their several positions and each latched in place by its tooth 29, and afterwards the bar 31 can be moved to locking position.

It will readily be perceived that my invention can be applied or adapted to similar situations in other machines than the one here shown.

Various changes may be made without departing from my invention.

What I claim as new and desire to secure by Letters Patent, is,

1. In a calculating machine, the combination of a supporting bar, a totalizer mounted on and adjustable along said bar, a locking bar extending lengthwise of said supporting bar and having a series of notches for locking said totalizer in its several adjustments, and means for moving said locking bar transversely into and out of engagement with said totalizer.

2. In a calculating machine, the combination of a supporting bar, a totalizer having sliding adjustment lengthwise of said bar, a notched locking bar carried by said supporting bar, and a shifting bar for moving said locking bar transversely into and out of locking engagement with said totalizer.

3. In a calculating machine, the combination of a supporting bar, a totalizer having sliding adjustment lengthwise of said bar, a locking bar carried by said supporting bar and movable transversely into and out of engagement with said totalizer, and a shifting bar movable lengthwise of said supporting bar and operating said locking bar.

4. In a calculating machine, the combination of a supporting bar, a totalizer adjustable lengthwise of said bar, a locking bar carried by said supporting bar, and a shifting bar movable lengthwise, said locking bar and shifting bar having a cam connection between them whereby the endwise motion of the shifting bar produces a transverse motion of the locking bar.

5. In a calculating machine, the combination of a supporting bar, a totalizer adjustable lengthwise of said bar, a locking bar carried by said supporting bar, and a shifting bar movable lengthwise, said locking bar and shifting bar having a cam connection between them whereby the endwise motion of the shifting bar produces a transverse motion of the locking bar, said cam connection having a dwell to hold said locking bar positively in locking position.

6. In a calculating machine, the combination of a supporting bar, a totalizer adjustable lengthwise of said bar, a locking bar movable transversely into locking engagement with said totalizer, a shifting bar movable lengthwise, and a plurality of pin and

- cam slot connections between said locking and shifting bars.
7. In a calculating machine, the combination of a supporting bar having a groove therein, a totalizer adjustable lengthwise of said bar, a locking bar and a shifting bar seated in said groove, means for preventing motion of said locking bar endwise of said supporting bar, and a cam connection between said locking and shifting bars whereby a longitudinal motion of said shifting bar causes a transverse motion of said locking bar into locking engagement with said totalizer.
- 15 8. In a calculating machine, the combination of a supporting bar, a totalizer adjustable lengthwise thereof, a locking bar movable into and out of locking engagement with said totalizer, a shifting bar for operating said locking bar, and a detent device for holding said shifting bar in either of its positions.
- 25 9. In a calculating machine, the combination of a totalizer supporting bar having a longitudinal groove, a totalizer adjustable lengthwise of said supporting bar, a locking bar mounted in said groove and shiftable into and out of engagement with said totalizer, end plates on said supporting bar preventing relative longitudinal motion of said supporting and locking bars, and means for shifting said locking bar.
- 35 10. In a calculating machine, the combination of a truck, a totalizer adjustably mounted on said truck, a coupling device adapted to be picked up and drawn along by said totalizer, and a toothed rack on said truck engaging said totalizer adjacent the point at which said coupling device engages.
- 40 11. In a calculating machine, the combination of a traveling truck, a totalizer adjustably mounted on said truck, means at the upper part of said totalizer for securing said totalizer in adjusted position on said truck,
- a coupling device that engages the lower part of said totalizer, and a toothed rack on said truck engaging said totalizer adjacent the point of engagement of said coupling device.
- 45 12. In a calculating machine, the combination of a traveling truck, a totalizer adjustable lengthwise of said truck, means at the upper part of the totalizer for securing it in adjusted position on said truck, a coupling device engaging the lower part of said totalizer, and a locking rack movable into and out of engagement with said totalizer adjacent the point of engagement of said coupling device.
- 50 13. In a calculating machine, the combination of a supporting bar, a totalizer adjustable longitudinally of said bar, a rack fixed to said bar, a spring actuated latch in the upper part of the totalizer and engaging said rack, and separate locking means for the lower part of the totalizer, said separate locking means being movable into use after the adjustment of the totalizer and the latching of its upper portion.
- 55 14. In a calculating machine, the combination of a supporting bar, a rack fixed to the upper part of said bar, a totalizer adjustable longitudinally of said bar, a spring actuated latch at the upper part of the totalizer for engagement with said rack, a lock or tooth on the lower part of the totalizer, and a rack movably mounted in said supporting bar and adapted to engage said lock or tooth after the totalizer has been adjusted and latched by said spring operated latch.
- 60 Signed at the borough of Manhattan, city of New York, in the county of New York and State of New York, this 21st day of June, A. D. 1921.
